UNITED STATES PATENT OFFICE.

RALPH HUSH, OF JOHANNESBURG, TRANSVAAL, SOUTH AFRICA.

MACHINE FOR BREAKING ORE AND OTHER MINERALS.

Application filed February 12, 1925, Serial No. 8,815, and in the Union of South Africa February 18, 1924.

This invention consists of improvements in machines of the jaw crusher type for breaking or crushing ore and other minerals, and is particularly applicable for reducing ore to a size suitable for introduction into a fine grinding machine. One feature of the invention can, however, be adopted in the construction of other types of jaw crushers, such as, for example, the "Blake" crusher.

According to this invention the swinging or movable jaw or stock is directly actuated or operated to cooperate with the stationary jaw, as for example, through the medium of connecting rods and eccentrics or their equivalent off the main driving shaft; the jaw is suspended from the upper end and the power is applied to it at the lower end, and the crushing of the material takes place between the point of suspension and the point of application of the power, thereby obtaining more efficient application of the power. The stationary jaw is provided with adjusting means which automatically accommodates itself to the positions taken up by the jaw after any adjustment, whereby the stationary jaw can be finely adjusted, easily and quickly, to obtain the desired size of product, the main frame being appropriately shaped or inclined to provide the requisite accommodation for the adjusting means.

The renewable wearing plates of the crushing jaws are formed with shallow and wide corrugations, as opposed to the ordinary V-shaped ribs or projections, which corrugations may be continuous for the full depth of the wearing plate. Alternatively, the corrugations may be formed on the plate extending for a portion—say half—of the depth thereof, and other corrugations, staggered in relation to the first-mentioned corrugations, may be formed on and extend for the rest—say half—of the depth of the plate. The staggering of the corrugations renders the plates interchangeable and also independently reversible or each capable of being inverted or turned end for end. This construction has the further advantage that the plate can be used for either the swinging or stationary jaw and obviates the necessity for providing different constructions of plates for each jaw as is the case with plates having continuous corrugations.

In applying that feature of the invention

which relates to the crushing jaws or wearing plates therefor to other types of jaw crushers, such as, for example, the "Blake" crusher, the shallow and wide corrugations on the working faces of the jaws or renewable wearing plates are preferably continuous, or run from the top to the bottom edges of said jaws or plates, or for the full depth thereof. As a result of this construction the jaws or plates are reversible or capable of being inverted or turned end for end.

The invention will be more fully described with the aid of the accompanying drawings, wherein—

Fig. 1 is a sectional elevation of a machine embodying the various features of the invention, the section being taken on line $z-z$ of Fig. 2.

Fig. 2 is a plan of the machine.

Fig. 3 is an elevation of one of the renewable wearing plates of the crusher jaws, detached.

Fig. 4 is a plan of Fig. 3.

Fig. 5 is a view of portion of a renewable wearing plate intended more particularly for use with jaw crushers of the "Blake" and similar types.

Fig. 6 is a plan view of the plates of the co-operating jaws of a crusher of the "Blake" type, and

Fig. 7 is a half-sectional elevation of the big end of one of the connecting rods.

Referring to the embodiment of the several features of the invention depicted in Figs. 1 to 4 and 7, the numeral 1 denotes the main frame of the machine, which, as shown in Figs. 1 and 2, is constructed to provide at one end a vertical housing or crushing chamber 1^a , and at the other end to form a support or framework to provide or carry the bearings 2, 3, for the driving shaft 4. Between the sides of the vertical housing 1^a and near both ends thereof are arranged shafts or pivots 5, 6, respectively. From the shaft 5 is suspended the swinging jaw 7, and in like manner from the shaft 6 is suspended the stationary adjustable jaw 8.

The rear or back end of the crushing chamber 1^a is inclined or sloped downwardly and rearwardly to the base, as indicated at 9, and the side plates 10, 11, of the rear portion of the main frame 1 are sloped

downwardly from the top of the crushing chamber 1^a to the base at 12. These rearwardly inclined side plates 10, 11, provide the bearings 2, 3, respectively, for the driving shaft 4, on which, between the side plates 10, 11, is secured the balance or flywheel 13 of the machine.

The driving shaft 4, at the one side, extends through the bearing 3 and has arranged thereon the fast and loose pulleys 14, 15, respectively; 16 being a pedestal or support for a bearing 17 in which the outer end portion of the shaft 4, beyond the loose pulley 15 is rotatably carried. 18 is a cap fixed to the outside of the bearing 17 for closing the bearing to form a lubricant holding chamber 19 in the bearing beyond the end of the shaft 4. 20 is a duct for leading lubricant to the hub of the loose pulley 15 from chamber 19; 21 being a pipe for leading lubricant into the chamber 19 from a lubricator or grease cup.

The driving shaft 4 is constructed with eccentric portions 22, 23, for operating the movable jaw 7. The motion is transmitted from said eccentrics 22, 23, to the movable jaw 7 by means of a pair of connecting rods 24, 25, placed at the outer sides of the main frame 1. The connecting rods 24, 25, are adjustable as to length, the parts of the big ends being provided with liners or distance pieces 26 placed between said parts—see Fig. 7.

27 is a plate fixed on the end of the shaft 4 at the outside of the big end of the connecting rod 24, for retaining the latter in position, and 28 is a distance piece or collar which also serves as a stop for the other connecting rod 25 between the latter and the fast pulley 14. 29 are holes formed in the shaft 4 between the bearings 2, 3, and the ends of the connecting rods 24, 25, respectively, which holes provide ducts or channels for the passage of lubricant.

45 The other ends of the connecting rods 24, 25, are connected to the lower end of the swinging jaw 7 by means of a shaft 30, said shaft 30 loosely fitting the hole 31 through the lower end of the jaw 7 and passing through holes 31^a in the sides of the main frame, which holes are large enough to allow of the movement of the shaft 30 therein. The connecting rods 24, 25, are attached to the ends of the shaft 30 by set screws 32.

55 The jaws 7, 8, are recessed on their opposing working faces to receive the wearing plates 33, 34, and wedge pieces 35 and screws 36 are provided for securing the plates 33, 34, in said recesses. The bottom of the recess and the lower side of the wedge 35 in each jaw or stock are made with corresponding tapers to allow of the wearing plates being renewed, or, if desired, being reversed and/or interchanged.

65 The adjusting means for the stationary

jaw 8 may, as shown, comprise an adjusting screw 36^a and screw-threaded handle or wheel-nut 37, the latter being fashioned with a projection 38 which is part of a sphere and projects into a correspondingly shaped recess 39 formed in a bracket or extension 40 provided on the frame 1 for supporting the adjusting means. The adjusting screw 36^a projects down the back of the stationary jaw 8 between it and the back wall of the crushing chamber 1^a, and at its lower end is pivotally attached, by means of pivot pin 40^a, to an adjusting block 41, which block, at the front, engages with the back of the stationary jaw 8, and at the other side, which is concave or of arcuate shape in cross-section, with a part 42 which is correspondingly convex. This latter part 42 is loosely attached to the adjusting block 41 by a screw 43 which allows of the requisite movement of the block 41 around the surface of the part 42. The part 42 on the opposite side or back is made plane and slidingly contacts with the rearwardly inclined wall 9 of the back of the crushing chamber 1^a.

As shown in Figs. 1 to 4, the wearing plates 33, 34, are formed with shallow and wide corrugations 44 extending for one-half the depth of the plate, and with other corrugations 45, staggered in relation to the corrugations 44, for the other half of the depth of the wearing plate. The inner ends of the raised portions of the corrugations 44 project between the ends of the relatively staggered raised portions of the corrugations 45, so that the raised or convex portions of the corrugations 44 merge into the concave portions between the relatively staggered, raised or convex portions of the corrugations 45, and vice versa. The corrugations of the wearing plates of the two jaws are such that those of the one jaw are disposed opposite to and co-act or co-operate with those of the other jaw, i. e., the convex portions of the corrugations of the one jaw are placed opposite to and co-act or co-operate with the concave portions of the other jaw in all positions of the wearing plates—see Figs. 1 and 2. The plates 33, 34, being of identical construction, it will be understood that they are interchangeable and independently reversible or capable of being turned end for end.

The corrugations 44, 45, run from top to bottom of the plates, and, as shown, preferably extend the full width of the jaws. The number and dimensions of the corrugations are designed to reduce the material to the desired size of product.

By the adoption of the wearing plates constructed as above described, I obtain greater durability and greater uniformity in the product obtained, without undue strain on the machine and with reduced power consumption.

In an opening 46 in the main frame 1

beneath the jaws 7, 8, there may be arranged a tray or receiver (not shown) for the crushed product, or the product can be delivered away from the machine by a chute 5 or hopper construction, or otherwise.

If desired, means may be provided for retracting the movable jaw 7 to take up any wear in the bores of the driving ends of the connecting rods 24 and/or on the ends of 10 the shaft 30, and so prevent knock. In Fig. 1 of the drawings, means provided for this purpose consists of a flat spring 47 adjustably fixed near the upper end to the frame 1 by means of a bolt 48, and at the lower 15 end attached by means of a hook-shaped bolt 49 to the lower end of the jaw 7. 50 is the adjusting nut for the bolt 49, and 51 a pin fixed across a recess 52 in the back of the jaw 7, with which pin 51 the hooked 20 extremity of the bolt 49 engages. An opening 53 is provided in the back of the frame 1 for the wing-nut 50 to move in and also to provide access to the back of the swinging jaw 7. 54 is a pin fitted in a hole in 25 the upper portion of the end of the frame 1 for engaging in a corresponding hole in the upper end of the spring 47, for retaining it in a central position.

55, 56, are renewable lining plates fitted 30 in recesses in the frame 1, at the sides of the crushing chamber 1^a, and fixed therein by bolts 57.

In the drawings the machine is provided 35 with fast and loose pulleys 14, 15, respectively, for driving it by power, but if the machine be designed for crushing samples, it may be operated by hand through the medium of a crank handle or lever fixed to the driving shaft 4.

40 Renewable, independently reversible and interchangeable wearing plates constructed with staggered wide and shallow corrugations, as above described, can with advantage be adopted in jaw crushers of other types, as for example, the "Blake" type, 45 whether the jaws be operated by the means above described, or otherwise.

In the modified form of the renewable 50 wearing plates shown in Figs. 5 and 6, suitable for a crusher of the "Blake" or similar types, the wide and shallow corrugations are continuous or run from the top to the bottom edges of the plates (or jaws). The 55 plates or the jaws themselves, constructed with the corrugated working faces, may be recessed or webbed at the back, as shown at 58 in Fig. 6, for the purpose of making them lighter, whilst affording the requisite strength. The plates constructed with continuous corrugations would be renewable and 60 reversible, but not being of identical construction, would not be interchangeable.

In some types of jaw crushers the fixed jaw 65 would probably require to be constructed with one extra corrugation, that is to say

it would be a corrugation wider than the swing jaw.

An advantage of constructing the wearing plates with the wide and shallow corrugations is that the passage of the material, and 70 particularly flat pieces, through the jaws without being reduced or crushed is prevented, and that an opening is provided, extending the full width of the jaws, of uniform width between the corrugations of the 75 two jaws. The long sweep or radius of the corrugations ensures that the hollow or concave parts of the corrugations of the plates (or jaws) shall be worn down uniformly 80 with the intervening convex or projecting parts, thereby retaining the corrugated formation of the plates (or jaws) during the whole of the time they are in use, or until they are worn out.

The alternating convex and concave formation of both the swing and fixed jaws ensures that the convex portions of the one shall enter the concave portions of the other, as shown in Fig. 6, which, as previously explained, results in uniform wear over the 90 width of the surface of the jaws and so materially increases the life of the plates or jaws.

For the purpose of facilitating the lining 95 of the big ends (or both ends) of the connecting rods 24, 25, an arcuate projection 59, as shown in the big end of one of the connecting rods in Fig. 7, is provided, which projection 59 forms part of the bore and serves for centering a mandrel around which 100 the molten metal is run in to line the bearing.

What I claim as my invention and desire 105 to protect by Letters Patent is:—

1. A machine for breaking ore and other 110 minerals, including a crushing chamber, an adjustable stationary jaw and a swinging jaw, means for directly actuating the swinging jaw to co-operate with the stationary jaw, and means for adjusting the stationary 115 jaw comprising a block arranged between the back of the stationary crushing jaw and the wall of the crushing chamber, one face of said block being constructed with a concave surface, a part arranged between the concave surface of the block and the wall of the chamber and having a convex surface corresponding to and co-acting with the concave surface of the block with which it contacts, and means for raising and lowering 120 the adjusting block, as set forth.

2. A machine for breaking ore and other 125 minerals, including a crushing chamber, a stationary jaw and a swinging jaw, means for directly actuating the swinging jaw to co-operate with the stationary jaw, and means for adjusting the stationary jaw comprising a block arranged between the back of the stationary crushing jaw and the wall 130 of the crushing chamber, one face of said

block being constructed with a concave surface, a part arranged between the concave surface of the block and the wall of the chamber and having a convex surface corresponding to and co-acting with the concave surface of the block with which it contacts, and means for raising and lowering the adjusting block, said means comprising a screw carried by an extension of the main frame 10 of the crushing chamber and a hand-wheel engaging said screw, the wheel and extension being constructed to provide a ball and socket bearing, as set forth.

3. A machine for breaking ore and other 15 minerals, including a stationary jaw and a swinging jaw, wearing plates for said crush-

ing jaws, said wearing plates being constructed with wide and shallow corrugations of uniform depth throughout the length of said corrugations, said corrugations extending for a portion only of the depth of the wearing plate, and with an equal number of other exactly similar and oppositely placed corrugations staggered in relation to the first-mentioned corrugations 25 for the remainder of the depth of the plate, whereby the plates are rendered both reversible and interchangeable, as set forth.

In testimony whereof I have signed my name to this specification.

RALPH HUSH.
